UNITED STATES PATENT OFFICE.

IRVING A. FEATHERMAN, OF BROOKLYN, NEW YORK.

CORNER FOR METAL BEDS.

Application filed July 3, 1922. Serial No. 572,361.

To all whom it may concern:

Be it known that I, IRVING A. FEATHERMAN, a citizen of the United States, residing at Brooklyn, in the county of Kings and 5 State of New York, have invented a certain new and useful Improvement in Corners for Metal Beds, of which the following is a specification.

My invention relates to corners for metal 10 beds adapted to support the posts and also the end rails, and has for its object to produce a corner that will give rigidity and strength to the completed structure and will also make it practically impossible for a 15 construction to be insecure, wobbly or loosely mated as to the parts joined to the corner. It is my purpose to so form my corners that when the posts are secured to the corner, the very connections in themselves will, of 20 necessity give added strength to the assembly.

I accomplish my objects by the construction hereinafter set forth, pointed out in my claim and illustrated in the accompanying 25 drawings, in which—

Fig. 1 shows a plan view of my improved corner, some of the parts being shown by the dotted lines;

Fig. 2 shows a side elevation view of the 30 same;

Fig. 3 shows a transverse sectional view of the same;

Fig. 4 shows a detail view of the spanner I employ and

Fig. 5 shows a portion of the frame of a bed disclosing the post and its manner of anchoring to the corner.

Referring to the accompanying drawings the reference numeral 10 is used to indicate 40 the body of a bed corner, provided with its tapering channel 11, to receive an end, or side rail (not shown) in which has been secured (by the chilling process) a rail 12. Thus far my construction does not materially differ from the usual and customary 45 construction.

To this corner 10, while being chilled, I add a flap, or flap 13, which preferably extends the full length of the corner, the flap and corner joining so as to form a 50 right angular joint, 14, as shown. A staple 15 is also secured in the corner, while being chilled, one of its ends being embedded in the flap and its other end embedded in the corner proper, the staple thus spanning the 55 right angular joint formed by the corner and the flap. The staple is preferably formed with lugs on its ends, as shown in Fig. 4 to provide for the flowing metal anchoring it securely in its seat. 60

The bed post is, obviously, square or oblong so as to be seated in the right angular joint, its sides flush up against the flap and the surface of the corner proper, the staple protruding through an orifice in the post 65 into the interior thereof. A wedge shaped pin is then inserted between the inner mating surfaces of the post and through the staples and pressure is applied to firmly seat the pin within the staple and the sides 70 of the post, thus forcing the post firmly against the sides of the flap and corner and anchoring it securely in that position.

Having thus described my invention what I claim and desire to secure by Letter Patent 75 of the United States is:

A corner for metal beds comprising a body portion and a flap portion formed at right angles thereon, a rail-attaching device on the body portion, a rail embedded in 80 the body portion and a staple adapted for attachment to a post spanning the angle formed by the said body and flap portions and having one leg embedded in the flap portion and the other leg embedded in the 85 body portion and passing through an opening in the embedded rail.

In testimony whereof, I have signed the foregoing specification.

IRVING A. FEATHERMAN.
